(57) **CLAIM**

The ornamental design for a hanging gardening system, as shown and described.

DESCRIPTION

FIG. 1 is an isometric view of a hanging gardening system, showing our new design;

FIG. 2 is a top side elevation view thereof;

FIG. 3 is a bottom side elevation view thereof;

FIG. 4 is a right side elevation view thereof;

FIG. 5 is a left side elevation view thereof;

FIG. 6 is a front plan view thereof; and,

FIG. 7 is a back plan view thereof.
